CLAIM

The ornamental design for an ink stamp, as shown and described.

DESCRIPTION

FIG. 1 is a perspective view of an ink stamp, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is another perspective view thereof; and,

FIG. 9 is an exploded perspective view of the ink stamp shown with environment.

The wire frame lines shown throughout the views are intended to indicate surface contour.

The contrast in shading types between straight occasionally broken line shading and stipple shading represents a contrast in appearance as shown.

The broken lines immediately adjacent the shaded areas represent the bounds of the claimed design while all other broken lines are directed to environment and are for illustrative purposes only; the broken lines form no part of the claimed design.
